UNITED STATES PATENT OFFICE.

FREDERICK PERCIVAL SMALL, OF RIDGEFIELD, NEW JERSEY.

COMBINED WAY-BILL AND ACCOUNTING-COUPON.

1,239,977.

Specification of Letters Patent. Patented Sept. 11, 1917.

Application filed January 3, 1917. Serial No. 140,337.

To all whom it may concern:

Be it known that I, FREDERICK P. SMALL, a citizen of the United States, and a resident of Ridgefield, in the county of Bergen and State of New Jersey, have invented a new and Improved Combined Way-Bill and Accounting-Coupon, of which the following is a full, clear, and exact description.

This invention relates to a combined way-bill and accounting coupon which is adapted to be secured primarily to a package of freight, express matter or the like to which it refers.

Among the objects of the invention is to provide a shipping device to be used by express companies or other carriers, the device being of a form adapted to be fastened on or accompany the package, thereby preventing the separation of the package and the accounting coupon or statement in transit from the originating point to the point of destination or delivery.

Another object of the invention is to produce a combined shipping device of the nature set forth consisting of a label, blank, or sheet comprising separable waybill, abstract, and statement coupons, the last being preferably in the form of a flap or extension of the waybill portion, the whole being so arranged or constructed that after the abstract is detached from the waybill portion, said waybill is foldable along a predetermined or weakened line, so as to lie over and slightly beyond the edge of the statement coupon in position to have paste applied directly to the back of the waybill label for the attachment thereof permanently to the package, leaving the statement coupon carried by the package face inward and in such condition or position as to be readily detached from the package at the delivery end of the route for return to the originating office.

Another object of the invention is to provide a combined waybill label and accounting device of such a nature that all of the several coupon portions shall bear similar or identifying indicia, so that while one of the coupons is permanently and securely fixed to the package, it may always be available for the reproduction of any other portion of the device that may become destroyed or lost.

In the accompanying drawings, Figure 1 is a face view of a preferred

form of the combined waybill and accounting coupon device; and

Fig. 2 is a perspective view indicating the appearance of the device while the receiving agent is in the act of detaching the return statement coupon to the originating office.

Referring now more particularly to the drawings, I show a shipping device in the nature of a sheet of paper comprising three main coupons and one or more extensions or flaps for attachment purposes. These coupons are represented at 10, 11, and 12 and may be described as abstract, waybill label, and statement coupons, respectively. The abstract and waybill label are connected along a weakened line 13 providing for the easy separation of the abstract from the portions below the same, and the waybill label and statement coupons are connected similarly along a crease or weakened line.

These several coupons are printed or otherwise arranged with correlated indicia or blanks for the addition of information pertaining thereto. For example, each coupon is dated according to the date of transaction which along with the weight of the package and the amount to be collected in the case of a C. O. D. delivery or the like is applied by the agent at the originating office. These coupons also bear the same serial number, as indicated at 15. The abstract and statement coupons also may carry the name of the consignee, as indicated at 16, for facilitating the identification of these parts after the statement coupon has been received back at the originating office where the abstract coupon is retained.

The abstract coupon is provided preferably with a binding margin 17 at its upper end, whereby the coupon 10 may be bound or attached with any suitable filing device at the originating office after it is detached from the waybill label along the line 13.

The manner of use of the device from this point may be briefly described as follows: After the coupon 10 is detached from the part 11, the operator folds the latter forwardly and downwardly around the line 14, bringing the waybill label face downward directly over the face of the statement coupon 12. The statement coupon is provided with a pasting strip or margin 18 connected thereto by means of a weakened line 19. In the folding of the waybill label over the statement coupon, the free edge of

the label extends beyond the weakened line 19 and overlaps therefore a portion, say, for example, one-quarter of an inch of the pasting strip 18. The operator then applies 5 paste to the then upper face or back of the waybill label, the paste covering all of such back and the exposed portion of the strip 18. After being thus pasted the operator turns the folded device over and applies it 10 directly to the package with the result that all of the coupon 11 is permanently fixed to the package and all of that portion of the strip 18 is likewise fixed to the package remote from the line 19. It will be noted, 15 therefore, that while the label 11 and strip 18 are thus secured rigidly and permanently to the package, the statement coupon 12 is secured to the package in a detachable manner, but with sufficient security, being at- 20 tached along its upper and lower edges to the pasted portions, to insure under ordinary conditions its safe transportation with the package. It will be noted also that the state- 25 ment coupon 12 will thus be carried on the package substantially flat and with its printed and inscribed face toward the package. After the package is received at its desti- 30 nation, the agent or other official at the delivery end will remove the coupon 12, as in- dicated in Fig. 2, either by pulling laterally 35 directly upon the same with his fingers or by the use of a knife or other instrument run along the weakened lines 14 and 19. The overlapping of the free edges of the label 11 beyond the lower edge of the coupon 12 insures 40 that none of the paste applied to the label and strip 18 will touch the detachable coupon 12. Thereby the easy detaching of the coupon 12 is assured.

40 I claim:

1. A blank of the nature set forth comprising detachably connected portions which are adapted to be used as a waybill label and an accounting statement coupon, said 45 label and coupon being connected but separable along a predetermined line, one of said portions being longer than the other and foldable therover, the free edge of the longer portion extending beyond the corre- 50 sponding edge of the other portion, and a pasting strip constituting an extension of the shorter portion and over which the free edge of the longer portion lies, said longer portion and the then exposed portion of the 55 pasting strip being adapted to receive an ad-

hesive whereby said longer portion and the strip may be attached permanently to a package, the statement coupon being thereby carried in an unpasted removable condition.

2. A blank of the character set forth con- 60 sisting of a sheet comprising three main coupon portions each connected to another along a weakened line, the several weakened lines being parallel to each other, one of said portions constituting an abstract to be re- 65 tained by the originating office, another of said portions constituting an accounting statement coupon and having along one edge a detachable pasting strip, said pasting strip and the third main portion being arranged 70 along opposite edges of the statement coupon, said third portion being foldable along the weakened line connecting it to the state- 75 ment coupon flatly down upon the face of the statement coupon and constituting a waybill label, the free edge of the label re- 80 mote from the folding line overlapping the aforesaid pasting strip, the then upper face of the label and the exposed portion of the pasting strip being then adapted to receive an adhesive for securing the label, the past- 85 ing strip and the statement coupon all flatly against a package leaving the statement coupon free of paste to be detached from the other portions just mentioned to be sent back 90 to the originating office for checking up in connection with the abstract portion first mentioned.

3. In a device of the character set forth, 95 a blank consisting of a sheet comprising a waybill label, a statement coupon detachably connected along a weakened line thereto, the waybill label being foldable forwardly and downwardly flatly upon the statement coupon, said label and coupon being provided with similar identifying indicia, and an extension 100 along the free edge of the statement coupon adapted to receive an application of paste simultaneously with the application of paste to the rear face of the waybill label, where- 105 by the statement coupon is adapted to be detachably secured to a package along its two opposite edges coincidentally with the operation of pasting the said waybill label and extension, but leaving the statement coupon unpasted and adapted to be severed along said weakened lines for return to the originating office.

FREDERICK PERCIVAL SMALL.
